CLAIM

The ornamental design for a combined printing toy and case therefor, as shown and described.

DESCRIPTION

FIG. 1 is a perspective view of a combined printing toy and case in an opened condition showing our new design;

FIG. 2 is another perspective view thereof with the printing frame removed and the toy type tray in an opened condition;

FIG. 3 is another perspective view thereof showing the removable elements in an exploded condition;

FIG. 4 is another perspective view thereof showing the design in a closed condition;

FIG. 5 is a side elevational view thereof, the side opposite being a mirror image; and

FIG. 6 is a rear elevational view thereof.

The characteristic feature of our design resides in the interior elements as best shown in FIGS. 1 through 3.
